GARMENT PAD

Samuel Freedman, Malden, Mass.

Application February 2, 1940, Serial No. 317,027

3 Claims.

(Cl. 2-268)

The invention relates to a garment pad and more especially to a shoulder pad for men's, women's and children's outer and inner garments.

The primary object of the invention is the provision of a pad of this character wherein the same when built within a garment will hold up the sleeve or give a stiffened fullness thereto above the armhole or at the shoulder area of said garment and such pad will be maintained in a fixed position without liability or tendency to roll up.

Another object of the invention is the provision of a pad of this character wherein a garment at the shoulders thereof will be possessed of a widened characteristic in that the sleeves will be sustained flared and lifted adjacent to the shoulders and will be prevented from collapsing at their upper ends to maintain the fullness and broadened characteristic.

A further object of the invention is the provision of a pad of this character wherein the same when placed within a garment will effect a shaping thereto with the upper ends of the sleeves in a lifted position to present a broad shoulder effect to the garment and maintain throughout the life thereof a fullness to the sleeves at their upper ends.

A still further object of the invention is the provision of a pad of this character wherein the shoulders and the upper ends of the sleeves of a garment will be prevented from sagging or losing a lifted appearance to the sleeves at the upper portions thereof and in this way establishing an attractive fashioning to the garment.

A still further object of the invention is the provision of a pad of this character, which is simple in its construction, thoroughly reliable and effective in its purpose, readily and easily built within a garment, maintaining a fixed and lasting shape thereto, and inexpensive to manufacture and install.

With these and other objects in view, the invention consists in the features of construction, combination and arrangement of parts as will be hereinafter more fully described in detail, illustrated in the accompanying drawing, which discloses the preferred embodiment of the invention and pointed out in the claims hereunto appended.

In the accompanying drawing:

Figure 1 is an elevation of a garment built with pads constructed in accordance with the invention.

Figure 2 is a fragmentary elevation showing 55

the pads in position for the proper locating thereof within a garment.

Figure 3 is a sectional view taken on the line 3-3 of Figure 4 looking in the direction of the arrows.

Figure 4 is a fragmentary end edge view.

Figure 5 is a plan view of one of the units of the pad.

Figure 6 is a plan view of the other unit of said pad.

Figure 7 is a sectional view taken on the line 7-7 of Figure 6 looking in the direction of the arrows.

Figure 8 is a plan view showing the several units of the pad joining together for its completion.

Similar reference characters indicate corresponding parts throughout the several views in the drawing.

20 Referring to the drawing in detail, A designates generally an outer body garment, in this instance representative of a jacket or coat. The body 10 of such coat is constructed as is conventional with a lining (not shown) and outer fabric material and the sleeves 11 are similarly constructed while adapted to be built into this garment at the shoulder areas 12 and at the upper enlarged sleeve ends 13, respectively, are the pads B constituting the present invention and hereinafter fully described.

30 Each pad B comprises a main or base unit 14 preferably constructed from cotton wadding 15 joined with a piece of fabric 16, the jointure being accomplished by bastings 17. The wadding 15 is of a formation so that the unit 14 tapers from a straight edge 18 to a curved or rounded edge 19, these edges meeting each other. Superimposed upon the unit 14 is a substantially crescent-shaped relatively stiff unit 20, which at the 35 concaved edge 21 is straightened and follows a straight stitch line 22 when stitched to the unit 14 while the convexed edge 23 is free at all times. This unit 20 is composed of a plurality of plies of canvas, cotton, silk or woolen fabrics, these being joined together by rows of stitches 24.

40 Each pad involving the units 14 and 20 when joined together, as hereinbefore stated, is built into the garment A so that the portion 25 of the unit 14 will extend inwardly of a shoulder area of the said garment. The portion 26 of this unit 14 and the unit 20 will lie within the upper end of the sleeve 13 and by the curvature of the pad in the building thereof into the garment A between the outer fabric and the lining of the body 45 and sleeve 13 causes the unit 20 to lift the upper

end of the sleeve giving a flared condition thereto and the portion 26 of the unit 14, which underlies the unit 20, assures a fullness to the upper end of the sleeve 13 without the possibility of the losing of the shape thereof or the sagging of the same.

The structural makeup of each pad with the units 14 and 20 when built within the garment will prevent the rolling up of the pad and thus result in getting out of place and the collapsing of the shoulders of the said garment or the upper ends of the sleeves thereof. The pads, there being two employed in each garment, one for each sleeve and shoulder, will positively hold up the sleeves and shoulders of the garment and give a broad shoulder effect thereto with a flare or fullness at the upper ends of the sleeves of such garment as well as a lifted appearance to the upper ends of the sleeves. The garment, by the use of the pads, will have shapeliness of the character before stated and this shaping will be maintained for the life of the garment without sagging appearance or the drooping of the shoulders and the upper ends of the sleeves.

What is claimed is:

1. A pad of the character described comprising a unit having opposite straight and rounded edges of wadding tapering from the straight to

the rounded edge, and a substantially crescent-shaped stiffened unit having the edge at the concaved side thereof joined with the first-named unit along a straight line crosswise thereof intermediate with respect to the straight and rounded edges.

2. A pad of the character described comprising a unit having opposite straight and rounded edges of wadding tapering from the straight to the rounded edge, a substantially crescent-shaped stiffened unit having the edge at the concaved side thereof joined with the first-named unit along a straight line crosswise thereof intermediate with respect to the straight and rounded edges, the said last-mentioned unit including a plurality of plies of material, and rows of stitches joining the said plies with each other.

3. A pad of the character described comprising a unit having opposite straight and rounded edges of wadding tapering from the straight to the rounded edge, and a substantially crescent-shaped stiffened unit having the edge at the concaved side thereof joined with the first-named unit along a straight line parallel with the straight edge of the first-mentioned unit and spaced therefrom.

SAMUEL FREEDMAN.
